UNITED STATES PATENT OFFICE.

MICHAEL B. BOWEN, OF DECATUR, ILLINOIS, ASSIGNOR TO FARIES MANUFACTURING COMPANY, OF DECATUR, ILLINOIS, A CORPORATION OF ILLINOIS.

DESIGN FOR AN ARM FOR LIGHTING FIXTURES.

60,975.

Specification for Design.

Patented May 23, 1922.

Application filed October 14, 1921. Serial No. 507,801. Term of patent 7 years.

To all whom it may concern:

Be it known that I, MICHAEL B. BOWEN, a citizen of the United States, residing at Decatur, in the county of Macon and State of Illinois, have invented a new, original, and ornamental Design for an Arm for Lighting Fixtures, of which the following is a specification, reference being had to the accompanying drawing, forming part thereof.

The figure is a side elevation of an arm for lighting fixtures, showing my new design.

I claim—

The ornamental design for an arm for lighting fixtures, as shown.

MICHAEL B. BOWEN.
